STROKE CONTROL MEANS FOR HYDRAULIC PUMPS AND MOTORS

**Roger F. Horton, Hempstead, N. Y., assignor, by
mesne assignments, to United Aircraft Corporation,
East Hartford, Conn., a corporation of
Delaware**

Application June 10, 1947, Serial No. 753,708

11 Claims. (Cl. 103—161)

1 This invention relates to apparatus for controlling the stroke of hydraulic rotary pumps and motors and the like.

It has heretofore been suggested to control the stroke of the pistons in a rotary pump or motor of the type in which a track ring surrounds the pistons, by varying the eccentricity of the track ring by means directly responsive to the pressure in the high pressure side of the fluid circuit or system in which the device is employed. Such regulation of the stroke of hydraulic pumps and motors is unsatisfactory because the stroke is varied from maximum to zero in direct proportion to increase in the pressure in the system and thus cannot develop the horsepower of which the system is capable. As pressure increases the track ring is moved proportionately in a direction from full stroke position to zero stroke position and the horsepower delivered by a pump or developed by a motor, is limited and held constant because the volume of fluid displaced decreases as the pressure increases.

It is an object of this invention to provide stroke control means not subject to the above stated disadvantage.

Another object of the invention is to provide a simple, practical, and efficient device for controlling the stroke of hydraulic pumps and motors which is not operative to decrease the stroke until the pressure in the system exceeds a given amount.

Another object of the invention is to provide stroke control means for an hydraulic power conversion unit which will not become operative to modify or limit the stroke until a critical pressure is reached and which will then serve to gradually decrease the flow by reducing the stroke without necessarily decreasing or limiting the speed of rotation of the unit.

Another object of the invention is to provide a rotary power conversion unit, of the type employing a track ring to control the length of the stroke of the pistons, including a member movable in a plurality of directions in response to increase in fluid pressure in the system comprising said unit, in combination with means for absorbing energy of the movement of said member in one direction up to a given amount thereby causing said means to move in the other direction above said given pressure thereby swinging the track ring to decrease its eccentricity and progressively limit the stroke of the pistons in response to increase in pressure above said given amount.

Another object of the invention is to provide an hydraulic rotary pump in which the volume

of fluid displaced per revolution remains constant up to a critical pressure and then decreases without substantially lowering the critical pressure throughout a range of movement from maximum stroke position to zero stroke position.

Another object of the invention is to provide automatic control means adapted to prevent overloading of the driven member in an hydraulic pump circuit, as well as overloading of the hydraulic motor itself, without limiting the flexibility of the pressure-flow relationship up to a maximum horsepower.

Another object of the invention is to provide pressure regulation means for an hydraulic motor which will permit the motor to develop a continuously increasing horsepower up to a given or critical pressure and then gradually decrease the stroke and the torque developed without speed change.

20 Other objects of the invention will be in part obvious or in part pointed out hereinafter.

The invention accordingly consists in the features of construction, combinations of elements, arrangements of parts, and in the several steps 25 and relation and order of each of said steps to one or more of the others thereof, all as will be pointed out in the following description, and the scope of the application of which will be indicated in the following claims.

30 The invention will best be understood if the following description is read in connection with the drawings, in which,

Figure 1 is a cross sectional view of a device embodying my invention, and which may be employed as a pump or motor equipped with apparatus embodying my invention in a position before critical pressure has been reached;

Figure 2 is a front elevational view of the device shown in Figure 1, partly cut away and 40 partly in cross section;

Figure 3 is a diagrammatic view showing the change in position of the pressure control means after critical pressure has been reached;

Figure 4 is a view similar to Figure 2 of another embodiment of the invention;

Figure 5 is a schematic view of an hydraulic circuit employing an hydraulic pump equipped with the pressure regulator means disclosed herein;

50 Figure 6 is a schematic view of an hydraulic circuit employing an hydraulic motor equipped with the pressure regulator means disclosed herein; and

Figure 7 is a detail cross sectional view taken 55 on the line 7—7 of Figure 3.

In the drawings the numeral 10 indicates the

casing or shell of an hydraulic pump or motor. Pivotally mounted within the casing on the ball pivot 12 is a track ring assembly comprising the outer track 14, and the inner track 16, separated from the outer track by the race or bearings 18.

Within the inner track 16 is the pintle 20 in which are the fluid conduits 22 and 24 which communicate through the branch passages 22^a and 24^a respectively with the grooves 23 and 25 respectively in the peripheral surface of the pintle. Surrounding the pintle 20 is a bearing ring 26 having the ports 28 therein at spaced intervals, and surrounding the bearing ring 26 is the rotor 30 having the cylinders 31 communicating with the ports 28 respectively. In the cylinders are the pistons 32 respectively which project from the cylinders and the outer ends of which rest against the inner surface of the inner track 16.

The axes of the rotor and of the track ring assembly are parallel. The center of the rotor is at 34. In the position of the track ring assembly as shown in Figure 1 its axis is at 36. The center of the track ring of course shifts as the track ring assembly swings on pivot 12 and this movement controls the stroke of the pistons, changing the stroke from maximum in the eccentric position of the track ring in relation to the rotor center shown in Figure 1 to zero stroke when the axes of the track ring and rotor coincide. As shown in Figure 1 the track ring assembly is in its extreme position to the right in Figure 1 as viewed by the reader, and abuts against the stop 38 carried by the pivoted arm 40 which forms part of the pressure control apparatus which will now be described.

The arm 40 is pivoted to the casing on pivot member 42 projecting inwardly from the casing wall and made hollow to provide a fluid passage as will be described. Behind the pivot 42 the arm comprises an elongated portion 44, the rear end 46 of which is turned inwardly substantially at a right angle and is cup shaped providing a space 48 adapted to receive one end of a coil spring member 50. The other end of spring 50 abuts against the inner surface of the cup-shaped flange 52 at the inner end of the adjustable screw member 54 which extends through the casing wall, and axially through the said space 48 of the arm portion 44, and said coil spring member 50, the head 55 of which is received in the recess 56 in the outer face of the casing.

The front end portion 60 of arm 40, through which pivot 42 extends, is inclined at an oblique angle with respect to the said rear portion 44, and constitutes a cylinder having the bore 62 extending axially from its inner end in which is received the inner end 64 of the piston 66. The outer end of piston 66 projects from bore 62 and is connected by pivot 68 to link 70 which in turn is pivoted on pivot 72 to the lug 74 on the outer surface of the outer track ring 14, the portion of said surface to which lug 74 is attached being cut away or flattened as at 76, thereby providing additional space between the track ring and casing to receive the control means. It will be noted that piston 66 and link 70 are at all times angularly related.

Propulsion fluid is led into bore 62, into the space beyond the inner end of piston 66, from the high pressure side of the fluid circuit in which the pump or motor is incorporated, through the opening 78 extending through the casing, the conduit 80 the inner portion 80^a of which is aligned and communicates with the hollow pivot

member 42, and the port 81 extending radially through the wall of member 42. Member 42 thus serves as a pintle on which cylinder 60 rotates and through which propulsion fluid is supplied to bore 62. The inner end of member 42 is press fitted into the discharge end of portion 80^a of conduit 80.

Spring 50 is designed so that it will be compressed by less force than is required to swing the track ring on its pivot and so increase in the pressure in the system acting in the bore 62 of cylinder 60 will first cause arm 40 to rotate in a clockwise direction on its pivot thus moving cylinder 60 away from piston 66 which movement is absorbed in compressing spring 50 until the cup-shaped end 48 of portion 44 of arm 40 comes into contact with the annular flange 58 on the head of the adjustable screw member 54. When arm 40 cannot swing further in a clockwise direction, because of end 48 of arm portion 44 coming into contact with flange 58 of member 54, see Figure 3, further increase in the fluid pressure will cause piston 66 to move outwardly in cylinder 60 thus exerting a thrust against link 70, causing it to rotate counter-clockwise and moving pivot 68 outwardly. A thrust is thus exerted against the track ring assembly tending to rotate it on its pivot 12 in a counter-clockwise direction, from full stroke toward no stroke position, against the spring 90 which is interposed between the casing and the track ring on the opposite side of pivot 12 from lug 74. Spring 90 is made strong enough to bias the track ring to full stroke position until the fluid pressure rises sufficiently to cause an opposing thrust to be exerted through link 70 as has been described. Due to the angular relation between link 70 and piston 66 a side load or reaction load will be imposed on the linkage during movement of the track ring toward zero stroke position. This side load will obviously be taken up by the walls of the cylinder 60. When the pressure rises above the predetermined critical amount the resistance of spring 90 is overcome progressively until the center of the track ring coincides with the center of the rotor which is the no stroke position. In this position the device if employed as a pump will not be operative to deliver any propulsion fluid but its rotor may continue to rotate and its rate of rotation may under certain circumstances increase. In this "no stroke" position if the device is employed as a motor, rotation of the rotor will cease and no fluid will flow through the device.

When the system pressure falls below the critical amount the force of the fluid pressure will again be fully absorbed by spring 50 and spring 90 will swing the track ring assembly on its pivot 12 in a clockwise direction all the way to maximum stroke position thus again making available the full horsepower of which the device is capable.

The ball bearing 12 on which the track ring assembly pivots is supported in the V-shaped groove 92 provided in the inner end of an adjustable screw member 94 extending through the casing wall with its head 96 received in the recess 98 in the outer surface of the casing. The shank of this screw may be reduced in diameter as at 100 (Fig. 2) and a packing ring 101 inserted around the shank in the resulting space to provide a fluid seal. The outer surface of the outer track ring 14 is grooved at 102 to receive and provide a cage engaging ball pivot 12. The track ring is prevented from being dislodged from its pivot by adjustable stop means which

as shown is the adjustable screw member 104 which extends through the casing wall opposite screw member 94. Member 104 is adjusted so that its inner end extends beyond the inner surface of the casing wall and approaches sufficiently close to the track ring to insure that the track ring cannot at any time get off or be dislodged from ball pivot 12.

An opening 78^a and a conduit 80^a, similar to opening 78 and conduit 80 respectively are provided in the casing wall opposite to opening 78 and conduit 80 respectively, and a recess 56^a is provided in the casing wall (and closed by a removable screw 57), opposite recess 56 so that the pressure regulating means described herein may be attached at the opposite side of the device, as shown in dotted lines in Figure 1, for use if opposite hand rotation of the rotor is desired. Similarly a boss 91^a may be provided on the inner surface of the casing opposite to the boss 91 to facilitate interposing spring 90 between the track ring and the casing on the right hand side of the device as viewed in Figure 1 if the pressure regulating means described herein are transferred to the left hand side of the device as viewed in Figure 1.

In Figures 5 and 6 hydraulic pump and motor systems respectively are shown diagrammatically. In the pump system shown in Figure 5 propulsion fluid is supplied to the pump from the reservoir through conduit 110, and is supplied from the pump to work through the conduit 112 which has therein the one way flow or check valve 114. From the work the spent fluid is returned to reservoir through conduit 120. The fluid is received by the pump at low pressure and is discharged through conduit 112 at high pressure and so a supply of propulsion fluid to operate the pressure control means described herein is obtained through conduit 116 leading from conduit 112 to the opening 78.

The motor system shown in Figure 6 is similar to the pump system shown in Figure 5 except that the direction of flow is reversed. The propulsion fluid is led from reservoir to the pump *p* through conduit 120 and from pump *p* to the motor through conduit 112, and the spent fluid is returned from the motor to reservoir through conduit 110. The supply of fluid for operating the control means described herein is obtained through conduit 116 leading from high pressure conduit 112 to the opening 78.

As seen in Fig. 6 a relief valve 124 is provided between the pump inlet line 120 and the pump discharge line 112 so as to prevent an unlimited build up of pressure in the line 112 and the motor when the stroke of the pistons in the motor approaches zero. Similarly a flow control by-pass 126 is provided across the pump inlet and outlet lines 120, 112 to by-pass some of the pump outlet flow not required by the motor at any instant. The by-pass 126 then also serves to prevent the locking of high pressure between the pump discharge and motor inlet when the system is stopped or at any time.

In Figure 4 is shown a modification of the stroke control means described above. In this embodiment the rotor assembly 140, indicated in dotted lines, is contained within a track ring assembly 142 which is mounted within casing 144 on pivot 146. Between the track ring and the casing, linkage is provided comprising a cylinder 148 pivoted to the casing at 150 having therein the piston 152 the outer end of which is connected by pivot 154 to the link 156 which is

connected to the track ring by pivot 158. Fluid from the high pressure side of the pump or motor system is supplied to cylinder 148 through flexible conduit 160 extending through the casing 144. As the fluid pressure increases in cylinder 148 piston 152 is forced out of cylinder 148 and in so doing moves the piston 154 in a direction to decrease the angle between link 156 and piston 152. This outward movement is absorbed by spring 162 which is interposed between the cylinder 148 and the casing wall one end being received in the hollow boss 149 integral with cylinder 148 and the other end being received in a hollow boss 163 on the inner surface of the casing, until the critical pressure is reached. After the critical pressure is reached further outward movement of piston 152 is translated into swinging movement of the track ring on its said pivot 146 causing it to swing in a counterclockwise direction, as viewed in Figure 4, against the resistance of spring 164, which is strong enough to originally bias the track ring to the full stroke position but not strong enough to resist the torque exerted through link 156 after the critical pressure has been reached. A stop member 166 is provided in the casing wall opposite spring 164 for limiting clockwise swinging movement of the track ring assembly and determining its maximum stroke position. It will be understood that the control means shown more or less diagrammatically in Figure 4, like the control means shown in Figures 1-3 will not affect any change in the position of the track ring until the critical pressure is reached, after which it will gradually reduce the stroke from maximum to zero, in direct proportion to the increase in fluid pressure above the critical amount.

It is desirable to control an hydraulic pump so that it will deliver as much fluid per unit of time at as high a pressure as the system will safely take, thereby obtaining the largest possible horsepower, and to avoid having the stroke decreased as the pressure in the system goes up but while it is still within a safe pressure range, thus causing the amount of fluid delivered to decrease, and thereby reducing the horsepower which can be developed. In other words it is desirable to have the volume of displaced fluid per revolution of the pump remain constant up to a critical pressure and then have output decrease while holding the critical pressure approximately constant even to zero fluid output.

In a motor it is desirable to have an automatic control which prevents overloading of the driven member as well as of the motor itself without limiting the flexibility of the pressure-flow relationship up to a maximum horsepower.

When pressure control means of the kind described herein is applied to a pump it permits the pump to deliver a maximum of fluid until the critical pressure of the device is reached whereupon the stroke will be gradually reduced.

When the pressure control means described herein is used as a motor it permits increase in horsepower output until the critical pressure for the device is reached after which the stroke of the motor will be gradually reduced.

It will thus be seen that there has been provided by this invention a method and apparatus in which the various objects hereinabove set forth together with many thoroughly practical advantages are successfully achieved. As various possible embodiments might be made of the mechanical features of the above invention and as the art herein described might be varied in vari-

ous parts, all without departing from the scope of the invention, it is to be understood that all matter hereinbefore set forth or shown in the accompanying drawings is to be interpreted as illustrative and not in a limiting sense.

What I claim is:

1. In a power translating device comprising, a casing, a rotor within said casing having a number of radial cylinders, and pistons projecting from the ends of said cylinders, bearings carrying said rotor for rotation about a fixed axis, a drive shaft extending into said casing and coupled to said rotor, and a track ring pivotedly mounted within said casing in controlling engagement with the outer ends of said pistons for determining the position of said pistons in said cylinders, the axis of rotation of said track ring being parallel to the axis of rotation of said rotor, fluid inlet and outlet passages extending through said casing and communicating with said cylinders, and means operative above a critical pressure for swinging the track ring on its said pivot and thereby varying the stroke of the said pistons in said cylinders comprising, linkage interconnected between the casing and the track ring and including a plurality of angularly related members one of which comprises, a portion extensible when subjected to a pressure above a given pressure, a fluid conduit interconnecting said portion and the high pressure side of said device, and means connected to said angularly related means adapted to absorb the energy imparted thereto by extension of said linkage up to a given amount.

2. In a power translating device comprising, a casing, a rotor within said casing having a number of radial cylinders, and pistons projecting from the ends of said cylinders, bearings carrying said rotor for rotation about a fixed axis, a drive shaft extending into said casing and coupled to said rotor and a track ring pivotedly mounted within said casing in controlling engagement with the outer ends of said pistons for determining the position of said pistons in said cylinders, the axis of rotation of said track ring being parallel to the axis of rotation of said rotor, liquid inlet and outlet passages extending through said casing and communicating with said cylinders and adapted to serve alternatively as high pressure or low pressure conduits respectively according to whether the device is used as a pump or a motor, means operative above a critical pressure for swinging the track ring on its said pivot and thereby varying the stroke of the said pistons in said cylinders comprising, linkage interconnected between the casing and the track ring including a portion extensible when subjected to a pressure above a given pressure, tending as it is extended by pressure above said given pressure to swing the track ring in a direction from maximum stroke position to no stroke position, a liquid conduit interconnecting said portion and the high pressure side of said device, and means interposed between the casing and the track ring, on the opposite side of the track ring pivot from said linkage, opposing movement of the track ring induced by the extension of said extensible portion of said linkage and tending to swing the track ring in the direction from no stroke position to maximum stroke position.

3. In a power translating device comprising a casing, a rotor within said casing having a number of radial cylinders and pistons projecting from the ends of said cylinders, bearings carrying said rotor for rotation about a fixed axis, a

drive shaft extending into said casing and coupled to said rotor, and a track ring pivotedly mounted within said casing in controlling engagement with the outer ends of said pistons for determining the position of said pistons in said cylinders, the axis of rotation of said track ring being parallel to the axis of rotation of said rotor, liquid inlet and outlet passages extending through said casing and communicating with said cylinders and adapted to serve alternatively as high pressure or low pressure conduits respectively according to whether the device is used as a pump or a motor, means operative above a critical pressure for swinging the track ring on its said pivot to thereby vary the stroke of the said pistons in said cylinders comprising, linkage interconnected between the casing and the track ring including a portion extensible when subjected to a pressure above a given pressure, and a liquid conduit interconnecting said portion and the high pressure side of said device, means interposed between the casing and the track ring on the opposite side of the track ring pivot from said linkage opposing movement of the track ring induced by the extension of said extensible portion of said linkage and tending to swing the track ring in a direction from no stroke position to maximum stroke position, and a stop member extending inwardly from the casing toward the track ring opposite the said track ring pivot.

4. In a power translating device comprising a casing, a rotor within said casing having a plurality of radial cylinders and pistons projecting from the ends of said cylinders, bearings carrying said rotor for rotation about a fixed axis, a drive shaft extending into said casing and coupled to said rotor, and a track ring pivotedly mounted within said casing in controlling engagement with the outer ends of said pistons for determining the position of said pistons in said cylinders, the axis of rotation of said track ring being parallel to the axis of rotation of said rotor, liquid inlet and outlet passages extending through said casing and communicating with said cylinders, means operative above a critical pressure for swinging the track ring on its said pivot in a direction to move its axis toward concentricity with the axis of said rotor and thereby reduce the stroke of the said pistons in said cylinders comprising, linkage interconnected between the casing and the track ring including a portion extensible when subjected to a pressure above a given pressure, a fluid conduit interconnecting said portion and the high pressure side of said device, a spring interposed between the casing and the track ring on the opposite side of the track ring pivot from said linkage tending to swing the track ring in a direction to move its axis away from concentricity with the axis of said rotor, the pivot for the track ring comprising a ball and means for positioning the ball in the casing, the outer face of said track ring being provided with a concavity to fit over said ball pivot, and stop means projecting from the casing wall and adapted to prevent the track ring from being displaced from its said pivot.

5. In a power translating device comprising, a casing, a rotor within said casing having a number of substantially radial cylinders therein and pistons projecting from the ends of said cylinders, bearings carrying said rotor for rotation about a fixed axis, a drive shaft extending into said casing and coupled to said rotor, and a track ring pivotedly mounted within said casing in

controlling engagement with the outer ends of said pistons for determining the position of said pistons in said cylinders, the axis of rotation of said track ring being parallel to the axis of rotation of said rotor and removable from concentricity to eccentricity therewith, liquid inlet and outlet passages extending through said casing and communicating with said cylinders and adapted to serve alternatively as high pressure or low pressure conduits according to whether the device is used as a pump or a motor, means operative above a critical pressure for swinging the track ring on its said pivot to thereby vary the stroke of the said pistons in said cylinders comprising, linkage interconnected between the casing and the track ring including a portion extensible when subjected to a pressure above a given pressure, a liquid conduit interconnecting said portion of the high pressure side of said device, means interposed between the casing and the track ring on the opposite side of the track ring pivot from said linkage tending to swing the track ring in the direction from no stroke position to maximum stroke position, the said pivot for the track ring comprising a ball, an adjustable screw extending through the wall of the casing and having a concavity in its inner end adapted to receive and provide a seat for said ball, the outer surface of said track ring including a concave portion which rests on said ball, and an adjusting screw extending through the casing wall and projecting toward the track ring to prevent said track ring from being unseated from said ball pivot.

6. In a power translating device comprising, a casing, a rotor within said casing having a number of radial cylinders and pistons projecting from the ends of said cylinders, bearings carrying said rotor for rotation about a fixed axis, a drive shaft extending into said casing and coupled to said rotor, and a track ring pivotally mounted within said casing in controlling engagement with the outer ends of said pistons for determining the position of said pistons in said cylinders, the axis of rotation of said track ring being parallel to the axis of rotation of said rotor, liquid inlet and outlet passages extending through said casing and communicating with said cylinders, means operative above a critical pressure for swinging the track ring on its said pivot to vary the stroke of the said pistons in said cylinders from maximum stroke toward zero stroke comprising, linkage interconnected between the casing and the track ring including a portion extensible when subjected to a pressure above a given pressure, a liquid conduit interconnecting said portion and the high pressure side of said device said linkage comprising, an arm pivotally mounted to the casing intermediate its ends one end of said arm comprising a cylinder, a piston in said cylinder projecting from the outer end of said cylinder, and a link interconnected between the outer end of said piston and the track ring, said link and piston together forming a toggle-like connection adapted as said piston moves out of its said cylinder to "break" and form a sharper angle, a conduit leading from the high pressure side of the device into the cylinder beyond the inner end of the said piston, a stop member adjacent the other end of said pivoted arm, and yielding means interposed between the said other end of said arm and said stop member adapted to offer less resistance to the pressure introduced into said cylinder than is required to move the piston in said cylinder to initiate move-

ment of the track ring, and other resilient means pressing against the track ring in a direction tending to resist movement of said piston in said piston cylinder in a direction whereby when liquid under pressure is introduced into the said cylinder in said arm the arm will first rotate against said first mentioned resilient means until further rotation is stopped by contact with said stop member whereupon said piston will move out of its said chamber in said arm and in so doing will cause said track ring to swing in a direction opposed by said second resilient member.

7. In a power translating device comprising, a casing, a rotor within said casing having a number of radial cylinders, and pistons projecting from the ends of said cylinders, bearings carrying said rotor for rotation about a fixed axis, a drive shaft extending into said casing and coupled to said rotor, and a track ring pivotally mounted within said casing in controlling engagement with the outer ends of said pistons for determining the position of said pistons in said cylinders, the axis of rotation of said track ring being parallel to the axis of rotation of said rotor, fluid inlet and outlet passages extending through said casing and communicating with said cylinders, linkage including a member variable in length in response to change in pressure interconnected between the track ring and the casing, a connection between said fluid passages and said member, and means rendering said linkage means inoperative to swing the track ring on its pivot until the fluid pressure exerted on said member exceeds a predetermined amount.

8. In a power translating device comprising, a casing, a rotor within said casing having a number of radial cylinders and pistons projecting from the ends of said cylinders, bearings carrying said rotor for rotation about a fixed axis, a drive shaft extending into said casing and coupled to said rotor, and a track ring pivotally mounted within said casing in controlling engagement with the outer ends of said pistons for determining the position of said pistons in said cylinders, the axis of rotation of said track ring being parallel to the axis of rotation of said rotor, liquid inlet and outlet passages extending through said casing and communicating with said cylinders and adapted to serve alternatively as high pressure or low pressure conduits respectively according to whether the device is used as a pump or a motor, means operative above a critical pressure for swinging the track ring on its said pivot and thereby varying the stroke of the said pistons in said cylinders comprising linkage interconnected between the casing and the track ring including a member variable in length in response to change in pressure and a link pivotally joined to said member between it and the track ring, means rendering said member sensible to change in pressure in the system, said link and said member being disposed so that the axis of the link and the axis of said member define an angle variable in response to movement of said member, and yielding means interposed between said linkage and the casing adapted to absorb the energy of movement of said linkage up to a given amount.

9. In a power translating device comprising, a casing, a rotor within said casing having a number of radial cylinders and pistons projecting from the ends of said cylinders, bearings carrying said rotor for rotation about a fixed axis, a drive shaft extending into said casing and coupled to said rotor and a track ring pivotally

11

mounted within said casing in controlling engagement with the outer ends of said pistons for determining the position of said pistons in said cylinders, the axis of rotation of said track ring being parallel to the axis of rotation of said rotor, liquid inlet and outlet passages extending through said casing and communicating with said cylinders and adapted to serve alternatively as high pressure or low pressure conduits respectively according to whether the device is used as a pump or a motor, means operative above a critical pressure for swinging the track ring on its said pivot and thereby varying the stroke of the said pistons in said cylinders comprising, linkage interconnected between the casing and the track ring comprising a member variable in length in response to change in pressure and a link pivotally joined to said member between it and the track ring, means rendering said member sensible to change in pressure in the system, said link and said member being disposed so that the axis of the link and the axis of said member define an angle variable in response to movement of said member, and yielding means interposed between said linkage and the casing adapted to absorb up to a given amount of energy of said linkage in moving in response to change in length of said member whereby no energy is transmitted to the track ring to swing it until said member is actuated by pressure in excess of said given amount after which the track ring is moved in proportion to increase in pressure above said given amount.

10. In a power translating device comprising, a casing, a rotor within said casing having a number of radial cylinders, and pistons projecting from the ends of said cylinders, bearings carrying said rotor for rotation about a fixed axis, a drive shaft extending into said casing and coupled to said rotor, and a track ring pivotedly mounted within said casing in controlling engagement with the outer ends of said pistons for determining the position of said pistons in said cylinders, the axis of rotation of said track ring about its pivot being parallel to the axis of rotation of said rotor, fluid inlet and outlet passages extending through said casing and communicating with said cylinders, actuating means engaging said ring for moving the track ring on its pivot from maximum stroke to zero stroke, said 50

12

means being responsive to increase in pressure of the fluid circulating through said device, and means for delaying the movement of said track ring and absorbing the energy of movement of said actuating means induced by increase in pressure of said fluid up to a predetermined amount.

11. In a power translating device comprising, a casing, a rotor within said casing having a number of radial cylinders, and pistons projecting from the ends of said cylinders, bearings carrying said rotor for rotation about a fixed axis, a drive shaft extending into said casing and coupled to said rotor, and a track ring pivotedly mounted within said casing in controlling engagement with the outer ends of said pistons for determining the position of said pistons in said cylinders, the axis of rotation of said track ring being parallel to the axis of rotation of said rotor, fluid inlet and outlet passages extending through said casing and communicating with said cylinders, means operative above a critical pressure for swinging the track ring on its pivot and thereby varying the stroke of said pistons in said cylinders comprising linkage interconnected between the casing and the track ring including a member variable in length in response to change in pressure and a link pivotally joined to said member between it and the track ring, and means rendering said member sensitive to change in pressure in the system, said link and said member being disposed so that the longitudinal axis of said link and the axis of said member define an angle variable in response to variation in length of said member.
